[54] **DYEING KERATINOUS FIBERS WITH N-ALKYL-N-CARBAMYLALKYL-ISOPICRAMIC ACID COMPOUNDS**
6 Claims, No Drawings

ABSTRACT: This disclosure is concerned with dyeing compositions containing certain N-alkyl-N-carbamylalkyl-isopicramic acid compounds and to methods of dyeing keratinous fibers with these compositions.

DYEING KERATINOUS FIBERS WITH N-ALKYL-N-CARBAMYLALKYL-ISOPICRAMIC ACID COMPOUNDS

This is a divisional application of Ser. No. 413,986 filed Nov. 25, 1964, now U.S. Pat. No. 3,420,883.

This invention relates to dyes for keratinous fibers such as hair and fur. It also relates to compositions for dyeing keratinous fibers comprising such dyes and to processes for dyeing keratinous fibers using such compositions.

The new dyes of the present invention are compounds of the general formula

where

N¹ is an alkylene group having up to 3 carbon atoms;
N² is an alkyl or hydroxyalkyl group having up to 3 carbon atoms, or the group —R¹—NH₂ and salts thereof. Preferably the salts are alkali or alkaline-earth metal salts or ammonium or substituted-ammonium salts.

Examples of substituted-ammonium salts are ammonium salts in which one or more of the hydrogen atoms of the ammonium radical is substituted by an alkyl group having up to six carbon atoms or by a hydroxyalkyl group having up to four carbon atoms or in which two hydrogen atoms of the ammonium radical are substituted by a group which forms with the nitrogen atom a heterocyclic ring.

As specific examples of metal salts are mentioned the sodium, potassium and calcium salts. As specific examples of substituted-ammonium salts are mentioned the mono-, di-, and tri-ethanolamino or -isopropanolamine, mono-, di-, and tri-methylamine, -ethylamine, -isobutylamine and morpholine salts. Salts derived from other amines or basic nitrogen-containing compounds may also be employed.

The above dyes of the invention color hair a violet shade (which is rare for a nitro dye) and can be used, for example, in the formulation of blonde, brown and grey hair colorants. The dyes of the invention are of particular value in the formulation of medium and dark brown hair colorants.

The preferred dyes of the invention are N-methyl-N-carbamyl-methyl-isopicramic acid and its alkali metal, alkaline-earth metal, ammonium and substituted-ammonium salts.

The invention also provides a composition for dyeing keratinous fibers, especially living hair, comprising a dye of the invention in aqueous solution. The pH of the solution of the dye may vary over a wide range but will usually be in the range pH 2 to 12. It is preferable to apply the dyes to living hair from solutions having a pH of less than 9 since the uptake by the hair of the dyes is greater at the lower pH, and at the same time the hair is left in a better condition. Furthermore, solutions of pH above 9 tend to shorten the life of permanent waves.

The dyes of the invention may be used with other suitable nitro dyes to produce blonde, brown and grey shades. When the violet dyes of the invention are used in conjunction with a yellow dye as in, for example, the formulation of a composition for producing brown or blonde shades, the yellow dye is preferably 2-nitro-N-methyl-N-acetyl-p-amino-phenol or a salt thereof or N-methyl-N-acetyl-isopicramic acid or a salt thereof, preferably an alkali metal, alkaline-earth metal, ammonium or substituted ammonium salt thereof. Compositions containing the violet dyes of the invention and these yellow dyes preferably have a pH in the range 6.5 to 7.5.

The violet dyes of the invention are also advantageously used with blue-violet to violet dyes being compounds having the general formula

where

R³ is an alkyl group or a hydroxyalkyl group having up to 4 carbon atoms; and

R⁴ is a hydroxyalkyl group having up to 4 carbon atoms; or salts thereof. Again, the preferred salts are the alkali and alkaline-earth metal salts and ammonium and substituted-ammonium salts.

Since these yellow dyes and blue-violet to violet dyes have similar chemical structures to the violet dyes of the invention, combinations of them possess useful properties. For instance, selectivity on certain hairs is minimized and also the fastness of the color of the dyed fiber is good. The combinations also have good stability on storage of the composition.

When formulating dyeing compositions comprising the dyes of the invention in their salt form, the salt may be added as such or it may be formed in situ by including in the formulation the acid form of the dye and the appropriate base.

The invention further provides a process of dyeing keratinous fibers using the above-mentioned compositions.

Dyes according to the invention can be prepared as illustrated in the following example 1.

EXAMPLE 1

25 Preparation of N-methyl-N-carbamylmethyl-isopicramic acid ammonium salt.

A 500-ml. three-necked flask equipped with an automatic stirrer and attached to an ice-mantle and condenser was used. 30 g. of acetamide were added to 300 ml. of water containing 30 12 ml. of glacial acetic acid and stirred until a clear solution was obtained at 48°-50° C. 30 g. of the ammonium salt of N-methyl-isopicramic acid were then added. After stirring for a short time, 19.2 g. of potassium hydroxide dissolved in 45 ml. of water were added dropwise over a period of 10 minutes. 35 The temperature was then gradually raised over a period of 20 minutes until the mixture refluxed at 101° C. After refluxing for 25 minutes the flask was cooled externally until the temperature had dropped to 65° C. A further addition of 15 g. of chloroacetamide and 6 ml. of glacial acetic acid was then made. 40 After stirring for a few minutes at 65°-70° C., 9.6 g. of potassium hydroxide dissolved in 22 ml. of water were added dropwise over a period of 5 minutes. The temperature was then gradually increased over a period of 15 minutes and the mixture refluxed for 25 minutes more. The mixture was then 45 poured into 1200 ml. of cold water. The addition of 22 ml. of concentrated hydrochloric acid was then made to make the solution acid to Congo Red Paper. The solution was cooled from 40° to 32° C. and fine reddish-brown needles of N-methyl-N-carbamylmethyl-isopicramic acid crystallized out. 50 On filtration, 30 g. of moist dyestuff cake were obtained.

The ammonium salt of N-methyl-N-carbamylmethyl-isopicramic acid was produced as follows. The filter cake of N-methyl-N-carbamylmethyl-isopicramic acid obtained above was mixed to a smooth paste with a solution of 1 volume of 55 ammonia (specific gravity 0.88) in 2 volumes of methyl alcohol. The dyestuff paste was then dried at 50°-60° C. in a vacuum oven at reduced pressure (60-70 cm. Hg.) and ground in a mortar. The yield of N-methyl-N-carbamylmethyl-isopicramic acid ammonium salt was 24.0 g. On recrystallization from boiling water the pure dyestuff was obtained in the form of fine brown crystals with an olive lustre having a melting point of 184°-186° C.

The corresponding alkali metal, alkaline-earth metal and substituted-ammonium salts are readily prepared in a similar manner by neutralizing the N-methyl-N-carbamylmethyl-isopicramic acid with, for example, sodium or potassium hydroxide, calcium carbonate, di-isobutylamine, mono-, di- or tri-ethanolamine or morpholine. The morpholine salt was obtained, on recrystallization from water, in the form of granular, black-violet, dull crystals which melted, with decomposition, at 171°-173° C. The diethanolamine salt was obtained in the form of brown prisms with an olive lustre melting at 155°-157° C. The monoethanolamine salt was obtained on recrystallization as dull, fine, violet-black, crystalline aggregates which had a melting point of 152°-154° C.

Compounds having a hydroxylalkyl group attached to the amino nitrogen atom can also be prepared in a like manner to that described above but starting from, for example, a salt of N-(2-hydroxyethyl)-isopicramic acid instead of N-methyl-isopicramic acid.

Salts of N, N-di-carbamylmethyl-isopicramic acid may be prepared as described in the above example by starting from the ammonium salt of isopicramic acid instead of from the salt of N-methyl-isopicramic acid.

Dyes having a N-ethyl or N-propyl group instead of a N-methyl group may be obtained, as described above by employing as starting material the ammonium salt of N-ethyl- or N-propyl-isopicramic acid instead of the ammonium salt of N-methyl-isopicramic acid.

Furthermore, compounds having a N-carbamylethyl or N-carbamylpropyl group instead of a N-carbamylmethyl group may be obtained by employing chloro-propionamide or chloro-butryramide instead of chloro-acetamide.

The N-methyl-N-carbamylmethyl-isopicramic acid obtained as described above, on recrystallization from boiling water gave the pure dyestuff in the form of fine, lustrous, brownish-violet needles of melting point 187°-189°C.

The invention is further illustrated by the following examples 2 to 6 of compositions for dyeing hair. In these examples the percentages are percentages by weight.

Example	Percent			
	2	3	4	5
Ammonium salt of N,N-di(2-hydroxyethyl)-isopicramic acid.	0.35	1.00	1.20	1.5000
Ammonium salt of N-methyl-N-carbamylmethyl-isopicramic acid.	0.10	0.12	0.15	0.1875
N-methyl-N-acetyl-isopicramic acid.	0.40	0.25	0.30	0.3750
N-methyl-N-acetyl-2-nitro-para-amino-phenol.		0.50	0.60	0.7500
Formamide.	5.00	5.00	5.00	5.0000
Lauryl polyethylene glycol [C ₁₂ H ₂₅ O(C ₂ H ₄ O) ₁₁ H].	5.00	5.00	5.00	5.0000
Perfume.	0.50	0.50	0.50	0.5000
Thickener [Carbopol 934 (a 2% w/w aqueous dispersion of a carboxylic-substituted vinyl polymer neutralized with potassium hydroxide)].	30.00	30.00	42.00	45.0000
Water.	To 100			

The following procedure was adopted in preparing the above compositions. The dyestuffs, formamide, lauryl polyethylene glycol and water and, in the case of example 6 the morpholine, were mixed and heated to 70°-75°C. A 2 percent w/w aqueous dispersion of Carbopol 934 was partly neutralized with 5N potassium hydroxide to a pH of 7.0 to 7.5 and perfume mixed in. The mixture containing the dyestuffs was then stirred slowly into the Carbopol 934 paste and stirring continued until a homogenous paste was obtained. Where necessary the pH of the paste was adjusted to 6.5 to 7.0 by the addition of 10 percent lactic acid or 10 percent monoethanolamine.

The above compositions gave (on heads with 30-70 percent white hair) natural shades with acceptable fastness to shampooing, light and perspiration. They also had acceptable fastness properties on permanently waved hair and were free from scalp staining and had a good conditioning effect on the hair. Example 2 gave a golden blonde shade; example 3 a light brown shade; example 4 a medium brown shade; example 5 a dark brown shade; and example 6 a darker brown shade.

As a result of salon tests, a pH of 6.5 to 7.0 was found to be the optimum value for the color uptake and for imparting a good conditioning effect to the hair. A viscosity of 400 to 800 centipoises gave the best results in color uptake and permitted the easiest application.

The compositions can be applied with a sponge or brush or from an applicator to either dry or previously shampooed and towel-dried hair.

What is claimed is:

1. A composition for the direct dyeing of keratinous fibers containing in aqueous solution an effective amount of a compound of the formula

5

4

10 where R¹ is alkylene having up to 3 carbon atoms; R² is a group selected from the class consisting of alkyl and hydroxylalkyl having up to 3 carbon atoms and the group —R—^{co}_{NH}—CL·NH₂ or salts thereof selected from the group consisting of the alkali metal, alkaline-earth metal, ammonium, and amine addition salts.

2. A composition as claimed in claim 1 wherein said aqueous solution also contains an effective amount of a yellow dyestuff selected from the group consisting of 2-nitro-N-methyl-N-acetyl-p-amino phenol, N-methyl-N-acetyl-isopicramic acid and salts thereof selected from the group consisting of alkali metal, alkaline-earth metal, ammonium and amine addition salts.

3. A composition as claimed in claim 1 wherein said aqueous solution also contains an effective amount of a blue-violet to violet dyestuff being a compound selected from the group consisting of compounds of the formula:

30

where R³ is a group selected from the class consisting of alkyl and hydroxylalkyl having up to four carbon atoms; and R⁴ is hydroxylalkyl having up to four carbon atoms; and salts thereof selected from the group consisting of alkali metal, alkaline-earth metal, ammonium and amine addition salts.

4. A composition as claimed in claim 1 wherein the compound is N-methyl-N-carbamylmethyl-isopicramic acid or a salt thereof selected from the class consisting of sodium, potassium, calcium, ammonium, monoethanolamine, diethanolamine, triethanolamine, monoisopropanolamine, diisopropanolamine, triisopropanolamine, monomethylamine, dimethylamine, trimethylamine, monoethylamine, diethylamine, triethylamine, monoisobutylamine, diisobutylamine, triisobutylamine and morpholine salts.

5. A composition as claimed in claim 1 wherein the compound is N-methyl-N-carbamylmethyl-isopicramic acid.

6. Process for the direct dyeing of keratinous fibers comprising applying to the fibers an effective amount of a composition containing in aqueous solution an effective amount of a compound of the formula:

60

70 where R¹ is alkylene having up to 3 carbon atoms; R² is a group selected from the class consisting of alkyl and hydroxylalkyl having up to three carbon atoms and the group —R—^{co}_{NH}—CO·NH₂ or salts thereof selected from the group consisting of the alkali metal, alkaline-earth metal, ammonium and amine addition salts.

UNITED STATES PATENT OFFICE
CERTIFICATE OF CORRECTION

Patent No. 3,617,166 Dated November 2, 1971

Inventor(s) Jerzy Josef Bartoszewicz

It is certified that error appears in the above-identified patent and that said Letters Patent are hereby corrected as shown below:

Column 1, lines 18-20 "N¹ is an alkylene group having up to 3 carbon atoms; N² is an alkyl or hydroxyalkyl group having up to 3 carbon atoms, or the group -R¹-NH₂l and salts thereof" should be --R¹ is an alkylene group having up to 3 carbon atoms; R² is an alkyl or hydroxyalkyl group having up to 3 carbon atoms, or the group -R¹-CO.NH₂; and salts thereof--.

line 52, "lower pH" should be --lower pHs--.

Column 2, line 21, "example li" should be --example 1.--.

line 29, "of acetamide" should be --of chloro-acetamide--.

Column 4, line 12, "group -R-CO-NH,-CL-NH₂" should be --group -R-CO-NH₂--.

lines 72 and 73, "-R¹-CO-NH₂" should be -- -R¹-CO-NH₂--

Signed and Sealed this
